(57) **ABSTRACT**

A chrysanthemum plant named 'Cronus' characterized by its medium sized blooms with yellow ray florets and prolific branching; natural season flower date September 2-8; blooming for a period of 5 weeks.

3 Drawing Sheets

1

BACKGROUND OF THE INVENTION

'Cronus' is a product of a breeding and selection program for outdoor pot mums (garden mums) which had the objective of creating new chrysanthemum cultivars with a decorative type flower, a natural season flower date around September 2-8; blooming for a period of 5 weeks. The new plant of the present invention comprises a new and distinct cultivar of Chrysanthemum plant 'Cronus' is a seedling resulting from the open pollination among groups of chrysanthemum cultivars maintained under the control of the inventor for breeding purposes. The new and distinct cultivar was discovered and selected as one flowering plant by Rob Noodeljik on a cultivated field in Rijsenhout Holland in September 2000. The plant has been asexually reproduced by cuttings in greenhouses at Rijsenhout Holland. The new cultivar has been found to retain its distinctive characteristics through successive propagations.

BRIEF DESCRIPTION OF THE DRAWINGS

The present invention of a new and distinct variety of chrysanthemum is shown in the accompanying drawings, the color being as nearly true as possible with color photographs of this type.

FIG. 1 shows a plant of the cultivar in full bloom.

FIG. 2 shows the various stages of bloom of the new cultivar.

FIG. 3 shows the petiole and foliage of the new cultivar.

DESCRIPTION OF THE INVENTION

This new variety of chrysanthemum is of the botanical classification *Chrysanthemum morifolium*. The observations and measurements were gathered from plants grown out door in Rijsenhout, Holland under natural day length and temperature and planted week 22 in 2000 and 2001. The natural blooming date of this crop was September 2-8 (week 36). The average height of the plants was 26 cms. No growth retardants were used. No tests were done on disease or insect resistance or susceptibility. No tests were done on cold or drought tolerance. This new variety produces medium sized blooms with yellow ray florets blooming for a period of 5 weeks.

2

From the cultivars known to inventor the most similar existing cultivar in comparison to 'Cronus' is 'Lisa' (U.S. Plant Pat. No. 8,992). When 'Lisa' and 'Cronus' are being compared the following differences are noticed: The differences of 'Lisa' and 'Cronus' are (1) Flower color. 'Cronus' is darker yellow. (2) Natural flowering date. 'Cronus' flowers earlier.

The following is a description of the plant and characteristics that distinguish 'Cronus' as a new and distinct variety. The color designations are taken from the plant itself. Accordingly, any discrepancies between the color designations and the colors depicted in the photographs are due to photographic tolerances. The color chart used in this description is: The Royal Horticultural Society Colour Chart, edition 1995.

Table 1. Botanical Description of cultivar 'Cronus'

- Bud:
Size.—Large; cross-section 1.2 cm, height 1.4 cm.
Outside color.—Yellow 9 B.
Involucral bracts.—2 rows, length 7 mm, width 3 mm.
Involucral bracts among disc-florets.—Not present.
Involucral bracts color.—Green 138 B.
- 20 Bloom:
Type.—Decorative.
Height.—Medium. 1.5-2.5cm.
Size.—Medium.
Fully expanded.—4.5-5.5 cm.
Number of blooms per branch.—Approx. 5blooms per branch.
Performance on the plant.—5 weeks.
Seeds.—Produced in small quantities, ovate grey-brown 199A, 1½ mm in length.
Fragrance.—Typical chrysanthemum, slightly.
- 25 Color:
Center of the flower (disc-florets visible in mature stage).—Immature yellow 12 A. Mature yellow 13 B.
Color of upper surface of the ray-florets.—Yellow 12 A.
Color of the lower surface of the ray-florets.—Yellow 9 B.

<i>Tonality from distance.</i> —A garden mum with yellow flowers and a yellow disc at mature stage.	<i>Stem color.</i> —Green 138 B.
<i>Color of the upper surface of the ray-florets at aging of the plant.</i> —Yellow 9 B.	<i>Stem strength.</i> —Strong.
Ray florets:	<i>Stem brittleness.</i> —Present.
<i>Texture.</i> —Upper and under side smooth.	<i>Stem anthocyanin coloration.</i> —Absent.
<i>Number.</i> —130–150.	<i>Length of lateral branch.</i> —From top to bottom 11–12 cm.
<i>Cross-section.</i> —Concave.	<i>Lateral branch color.</i> —Green 138 B.
<i>Longitudinal axis of majority.</i> —Reflexing.	<i>Lateral branch, attachment.</i> —Brittle.
<i>Length of corolla tube.</i> —Medium. 0.6–1.0 cm.	<i>Branching (average number of lateral branches).</i> —Good with 6–7 breaks after pinching.
<i>Ray-floret margin.</i> —Entire.	<i>Peduncle length.</i> —2.5–3.5 cm.
<i>Ray-floret length.</i> —2.2–2.5 cm.	<i>Peduncle color.</i> —Green 138 B.
<i>Ray-floret width.</i> —0.4–0.6 cm.	<i>Natural season blooming date.</i> —September 2–8.
<i>Ratio length / width.</i> —Medium.	Foliage:
<i>Shape of tip.</i> —Rounded.	<i>Color.</i> —Upper side yellow-green 147 A. Under side yellow-green 147 B.
Disc florets:	<i>Size.</i> —Small; length 4.5 cm, width 4.5 cm.
<i>Disc diameter.</i> —0.3–0.5 cm.	<i>Quantity (number per lateral branch).</i> —6–7.
<i>Distribution of disc florets.</i> —Numerous, sometimes visible at mature stage.	<i>Shape.</i> —Round.
<i>Shape.</i> —Tubular.	<i>Texture upper side.</i> —Glabrous.
<i>Color.</i> —Yellow 13 B.	<i>Texture under side.</i> —Pubescent.
<i>Receptacle shape.</i> —Conical raised.	<i>Venation arrangement.</i> —Palmate.
Reproductive organs:	<i>Shape of the margin.</i> —Serrated.
<i>Stamen (present in disc florets only).</i> —Thin.	<i>Shape of base of sinus between lateral lobes.</i> —Round.
<i>Stamen color.</i> —Yellow-green 144 A.	<i>Margin of sinus between lateral lobes.</i> —Diverging.
<i>Pollen.</i> —Sometimes present.	<i>Shape of base.</i> —Acute.
<i>Pollen color.</i> —Yellow 12 A.	<i>Apex.</i> —Cuspidate.
<i>Styles.</i> —Thin.	
<i>Style color.</i> —Yellow-green 144 A.	
<i>Style length.</i> —3 mm.	
<i>Stigma color.</i> —Yellow-green 144 A.	
<i>Stigma width.</i> —1 mm.	
<i>Ovaries.</i> —Enclosed in calyx.	
Plant:	
<i>Shape.</i> —When grown as a spray type pot-mum, outdoor mounded and round.	
<i>Growth habit.</i> —Short.	
<i>Growth rate.</i> —Slow.	
<i>Height.</i> —26 cm.	
<i>Width.</i> —26–30 cm.	

<i>Stem color.</i> —Green 138 B.
<i>Stem strength.</i> —Strong.
<i>Stem brittleness.</i> —Present.
<i>Stem anthocyanin coloration.</i> —Absent.
<i>Length of lateral branch.</i> —From top to bottom 11–12 cm.
<i>Lateral branch color.</i> —Green 138 B.
<i>Lateral branch, attachment.</i> —Brittle.
<i>Branching (average number of lateral branches).</i> —Good with 6–7 breaks after pinching.
<i>Peduncle length.</i> —2.5–3.5 cm.
<i>Peduncle color.</i> —Green 138 B.
<i>Natural season blooming date.</i> —September 2–8.
Foliage:
<i>Color.</i> —Upper side yellow-green 147 A. Under side yellow-green 147 B.
<i>Size.</i> —Small; length 4.5 cm, width 4.5 cm.
<i>Quantity (number per lateral branch).</i> —6–7.
<i>Shape.</i> —Round.
<i>Texture upper side.</i> —Glabrous.
<i>Texture under side.</i> —Pubescent.
<i>Venation arrangement.</i> —Palmate.
<i>Shape of the margin.</i> —Serrated.
<i>Shape of base of sinus between lateral lobes.</i> —Round.
<i>Margin of sinus between lateral lobes.</i> —Diverging.
<i>Shape of base.</i> —Acute.
<i>Apex.</i> —Cuspidate.

TABLE 2

Differences with the comparison varieties		
	'CRONUS'	'LISA'
Color of the upper surface of the ray-florets	Yellow 12 A	Yellow 4 B
Natural flowering date	September 2–8	September 20–27

I claim:

1. A new and distinct variety of chrysanthemum plant as described and illustrated.
